HIS ATTORNEY

UNITED STATES PATENT OFFICE.

EDWIN E. BARNEY, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 923,106.

Specification of Letters Patent.

Patented May 25, 1909.

Application filed August 16, 1905. Serial No. 274,407.

To all whom it may concern:

Be it known that I, EDWIN E. BARNEY, citizen of the United States, and resident of Syracuse, in the county of Onondaga and 5 State of New York, have invented certain new and useful Improvements in Type-Writing Machines, of which the following is a specification.

My invention relates more especially to 10 the carriage feeding mechanism of type-writing machines embodying an escapement wheel, and has for one of its objects to provide a back stop (that is, a stop for preventing a reverse or backward movement of the 15 escapement wheel when the carriage is returned from left to right to begin a new line of writing) of the general character of that shown in the U. S. patent to Carl Gabrielson, No. 717,837, dated January 6th, 1903, in 20 connection with a "reverse feed" escapement, that is, an escapement by which the carriage is permitted to feed in letter space direction during the depression of a space key or printing key.

25 Another object of the invention is to provide an improved construction of "reverse feed" escapement.

Other objects will subsequently appear.

To these ends the invention resides in the 30 features of construction, combinations of devices and arrangements of parts to be hereinafter fully described and particularly pointed out in the claims.

In the accompanying drawings, Figure 1 35 is a vertical front to rear sectional view, taken about centrally, of so much of a type-writing machine as is necessary to a clear understanding of my invention. Fig. 2 is an enlarged fragmentary sectional view 40 taken on a plane represented by the line $x-x$ of Fig. 1. Fig. 3 is an enlarged elevation of the dog carrier or rocker and the parts mounted thereon, as viewed from the left side of the machine. Fig. 4 is a view 45 corresponding to Fig. 3, but taken from the opposite or right side of the machine. Fig. 5 is a top plan view of the parts shown in Figs. 3 and 4. Fig. 6 is an enlarged rear elevation of the dog carrier and its associate 50 parts, some of which are broken away for the sake of clearness, said view also showing the lower portion of the escapement wheel. Fig. 7 is an enlarged fragmentary rear elevation of the combined forward or holding dog 55 and escapement wheel stop, together with

the lower portion of the escapement wheel, the escapement wheel stop being shown in arresting position. Fig. 8 is an enlarged perspective view of the combined holding dog and escapement wheel stop. Fig. 9 is 60 an enlarged perspective view of the rear or stepping dog; and Figs. 10, 11 and 12 are diagrammatic views illustrating the various relations between the escapement dogs and the teeth of the escapement wheel. 65

My invention is illustrated as applied to a machine having the general characteristics of the Monarch typewriter, although differing from the latter somewhat in detail. It is to be understood, however, that the invention may be adapted to other forms of writing machines. 70

In the drawings, the framework of the machine is shown as comprising a base 1, corner posts 2 and a top plate 3. Key levers 4 are 75 fulcrumed on a fulcrum plate 5 fixed at the rear of the base. Pivoted at 6 to each key lever is a sub-lever 7, the lower portion whereof is slotted to coöperate with a fixed abutment 8 and the upper end whereof is connected by a link 9 with a type bar 10 which is one of a series of type bars mounted on a 80 segmental type bar support 11. The type bars may, as herein shown, each be arranged in a radial slot 12 in said support and pivoted on a segmental fulcrum wire 13, or said type bars may be mounted in any other suitable manner. The type bars are adapted to co-operate with the front face of a cylindrical platen 14 mounted on an axle 15 having its 85 ends pivotally supported in side bars 16 projecting forwardly from a back bar 17, the side bars 16 and back bar 17 comprising the platen carrier. The top and bottom faces of the back bar 17 are formed with longitudinal 90 grooves which receive anti-friction balls 18, said balls also coöoperating with grooves formed in fixed rails 19 and 20 secured to standards 21 mounted on the top plate 3. 95

A carriage feed rack 22 of the usual construction is carried by the platen carrier and normally meshes with a feed pinion 23 fixed at the forward or front end of a short shaft 24, which has its bearings in a bracket 25 fixed to the top plate of the machine. A feed or escapement wheel 26 is loosely mounted on the rear portion of the shaft 24 and has secured to its rear face a ratchet wheel 27. Engaging the teeth of the ratchet wheel 27 are 100 spring pawls 28 secured to a housing 29 105

which is fixed by means of screws 30 to the rear end of the shaft 24. When the carriage is fed in letter space direction it will be understood that the engagement of the pawls 28 with the ratchet wheel 27 will cause the escapement wheel 26 to rotate with the shaft 24, but when the carriage is moved from left to right across the top plate to begin a new line, the pawls 28 will slide over the teeth of the ratchet wheel 27, and the rotation of the shaft 24 will consequently not affect the escapement wheel 26. It will, of course, be understood that if during the movement of the carriage in either direction the feed rack 22 is disengaged or separated from the feed pinion 23, neither the shaft 24 or escapement wheel 26 will be affected. The arrangement and construction of the parts hitherto described is not novel and it is thought unnecessary to explain them in greater detail.

A dog carrier or rocker comprising a rock shaft 31, a vertically disposed arm 32 and a horizontally disposed arm 33 is pivoted at 34 in ears 35 extending rearwardly from a bracket 36 depending from the top plate. The dog rocker is provided with the usual restoring spring 37, and the arm 32 carries an adjustable screw stop 38 which is adapted to contact with the bracket 36 to limit the forward movement of the rocker, while the arm 33 is provided with an adjustable screw stop 39 which is adapted to contact with the bottom of the bracket 36 to limit the rearward movement of said rocker. Normally the restoring spring 37 maintains the dog rocker in the position illustrated in Fig. 1 with the limiting stop 39 in contact with the bracket 36.

Near its upper end the arm 32 of the dog carrier or rocker is provided with ears or lugs 40, 41 and 42, which, viewed from the rear of the machine, project toward the right from the right-hand face of the arm 32. The ears are perforated to receive a short shaft 43 which serves as a pivot for two escapement dogs 44 and 45, the forward dog being arranged between the ears 41 and 42 and the rear dog 45 between the ears 40 and 41. The inner faces of the dogs above the pivots are provided with studs or pins 46 and 47, about which are coiled light wire springs 48 and 49 housed in depressions formed in the arm 32 of the rocker. Said springs tend constantly to press the upper arms of the dogs away from the face of the dog rocker and to hold the tails 44^a and 45^a of said dogs in contact with the face of the dog rocker. The forward dog 44 has an arm 50 projecting leftward from near its upper end, as viewed from the rear of the machine, the arm 50 terminating in a stop portion 51. The rear dog 45 has the usual beveled back and in addition is provided with a clearance bevel 45^b at its entering edge, whereby said edge is made thinner than the remaining part of the dog; the direction of the bevel being at an angle to the

entering edge of the dog and the plane of the bevel intersecting the plane of the back of the dog. Said rear dog has secured to it as by a rivet 52 a strap 53 which has its rear end bent around the dog 45 so as to prevent any turning of the strap 53 on its rivet. The free or forward end of the strap 53 is adapted to contact with the forward dog 44. As seen in Fig. 1, the forward end of the arm 33 of the dog rocker is connected by a link 54 with a universal bar frame 55 having a pivot rod 56 supported in the sides of the base 1 and carrying a universal bar 57 which extends from side to side of the machine beneath the series of key levers.

Depending from the platen carrier is a stud 58 which is connected by a strap 59 with a spring drum 60 of ordinary construction, said spring drum containing a carriage main spring which constantly tends to draw the platen carrier and platen leftward across the top plate of the machine.

As hitherto stated the dog rocker is normally maintained in the position indicated in Fig. 1, from an inspection of which it will be noted that the forward dog 44 is normally engaged with one of the teeth of the escapement wheel 26. Fig. 6 also shows this normal engagement of the parts which is further diagrammatically illustrated in Fig. 10, wherein the tooth of the escapement wheel with which the dog 44 is engaged is indicated by the reference character *b* and the next succeeding tooth by *c*. The main spring tends to turn the escapement wheel 26 in the direction of the arrow in Fig. 6 and is sufficient to overcome the force of the dog spring 48, compressing the latter until the upper arm of the dog 44 contacts with the arm 32 of the dog rocker, as indicated in said Fig. 6. It is apparent from an inspection of said figure that in this position of the dog 44 the stop 51 is out of the path of the teeth of the escapement wheel.

The operation of the escapement mechanism to permit of the letter space feeding movement of the platen and platen carrier will now be described. When any key lever 4 is adequately depressed, the type bar associated with the depressed key lever is caused to swing upwardly to coöperate with the platen in a known manner, and at the same time said key lever, contacting with the universal bar 57, will swing the latter downwardly about its pivots, causing the downward movement of the link 54 and swinging the dog rocker forward from the position indicated in Fig. 1, until the limiting stop 38 contacts with the rear face of the bracket 36. As the dog rocker moves forward the front or holding dog moves forward out of contact with the tooth *b* of the escapement wheel 26. As soon as it is free from the escapement wheel the dog 44 will, under the influence of the dog spring 48, be

swung away from the face of the arm 32 of the dog rocker, the movement of the dog continuing until its tail 44^a contacts with said arm 32. The parts are so proportioned and adjusted that as the tail of the dog 44 contacts with the arm of the dog rocker the part of said dog between its pivot and its working face will contact with the strap or arm 53 fixed to the rear dog 45.

From an inspection of Fig. 6 it will be noted that the rear or stepping dog 45 is normally maintained by the dog spring 49 away from the face of the vertical arm of the dog rocker and with the tail 45^a of said dog in contact with said vertical arm. The normal position of the stepping dog 45 is such that during the forward movement of the dog rocker said dog will move forward to the right of the engaged tooth *b* of the escapement wheel (considered from the rear of the machine), the clearance bevel 45^b permitting the dog 45 to pass readily behind the tooth *b*, so that as soon as the dog 44 has been carried by the dog rocker forward out of contact with the tooth *b* the escapement wheel 26 will be turned under the influence of the main spring in the direction of the arrow in Fig. 6. The rotary movement of the escapement wheel will bring the next succeeding tooth *c* into contact with the stepping dog 45 and overcoming the tension of the dog spring 49, will swing the dog 45 about its pivot 43 until said dog contacts with the arm 32 of the dog rocker. This swinging movement of the stepping dog 45 will be transmitted through the strap or arm 53 to the holding dog 44, causing the latter to move simultaneously with the stepping dog 45 until it is brought to a stop against the arm 32 of the rocker. The two dogs will, at the termination of the forward movement of the dog rocker, be in the position illustrated in Fig. 11 with their working faces in the same plane, which is also the plane of the working face of the tooth *c* of the escapement wheel. It will be apparent that the latter has, during the forward movement of the dog rocker, escaped or moved one tooth in letter space direction, thereby permitting the platen carrier and platen to move a letter space distance under the pull of the main spring. The escapement devices are also operated in the manner above described when the space bar (not shown) is depressed.

When the depressed printing key 4 or the space bar is released, the dog rocker will be swung back to normal position under the influence of its restoring spring 37. As soon as the stepping dog 45 has moved far enough to the rear to pass out of contact with the tooth *c* of the escapement wheel, it will be swung away from the dog rocker by the dog spring 49 and will assume the position indicated in Fig. 12. Before the disengagement 60 of the stepping dog 45 from the tooth *c*, the

holding dog 44 moves rearwardly into engagement with said tooth so movement of the escapement wheel is prevented when the stepping dog 45 disengages. The position of the parts at the termination of the rearward movement of the dog rocker is indicated in Fig. 12 and it will be noted from an inspection of said figure that the escapement members are again in a relation corresponding to that illustrated in Figs. 6 and 10, except for the fact that the tooth *c* has taken the place occupied by the tooth *b* in said last mentioned figures.

When the escapement members are in normal relation, if the carriage be retracted from left to right, as to begin a new line, the pull of the main spring is withdrawn from the escapement wheel 26, and the friction of the connecting parts, such as that between the pawls 28 and ratchet wheel 27, would, but, for my present invention, turn the escapement wheel in the reverse direction, as indicated by the arrow in Fig. 7. This reverse movement of the escapement wheel is assisted to some slight degree by the dog spring 48 which moves the dog 44 to the position indicated in Fig. 7 as soon as the reverse movement of the escapement wheel has proceeded far enough to permit. From an inspection of Fig. 7 it will be observed that the movement of the dog 44 under the influence of the spring 48 has brought the stop 51 into the path of the teeth of the escapement wheel, the back faces of said teeth as indicated at 26^a, being cut on an arc struck from the short shaft 43 as a center, so as to permit a ready entrance of the stop 51 into the path of the teeth, and so that said stop intercepts the escapement wheel and prevents reverse movement thereof, as indicated in said Fig. 7. The back face of the tooth *a* of the escapement wheel, which tooth is the one immediately to the left (as viewed in Fig. 7) of the engaged tooth contacts with the stop 51 which is prevented from turning farther to the right about the pivot 43 because of the contact of the tail 44^a of the dog 44 with the arm 32 of the dog rocker.

It will be seen that I have provided a carriage feeding mechanism wherein the holding member of the escapement mechanism, that is, the dog 44, is normally in engagement with the toothed escapement member, that is, the escapement wheel 26, and that when said dog 44 is disengaged from one tooth of the escapement wheel 26 the stepping member, or the dog 45, will be engaged by the next succeeding tooth of the escapement wheel and the platen carrier and platen will be fed a unit or letter space distance leftward across the top plate. It will further be noted that as soon as the holding dog 44 is disengaged from the escapement wheel it will be swung by its spring away from the dog rocker, but that as soon as the stepping dog 130

45 is engaged by the escapement wheel, a part of said stepping dog will swing said holding dog back again to normal position in contact with the dog rocker.

5 It will furthermore be seen that I have provided in connection with a carriage feeding mechanism which permits a letter space movement of the platen on the down stroke or depression of a key and which is commonly known as a "reverse feed" escapement mechanism, a stop member or back stop which is connected with the holding dog mounted on the vibratory dog carrier and is adapted to be automatically positioned 10 to prevent reverse movement of the escapement wheel when the carriage is returned or thrust back from the left to the right across the top plate of the machine.

Various changes in the construction of the 20 parts and in their arrangement may be made without departing from the spirit and scope of my invention.

What I claim as new and desire to secure by Letters Patent, is:—

25 1. In a typewriting machine and in a reverse feed escapement, the combination of a carriage, printing keys, an escapement wheel, a vibratory dog carrier, a pivoted spring pressed holding dog mounted thereon 30 and normally in engagement with the escapement wheel, and a pivoted spring-pressed stepping dog adapted to invariably permit a letter space movement of the carriage upon the depression of a finger key, said stepping 35 dog as it moves being also adapted to move said holding dog.

2. In a typewriting machine, the combination of a carriage, printing keys, an escapement wheel, a vibratory dog carrier, a pivoted spring-pressed holding dog mounted 40 thereon and normally in engagement with

the escapement wheel, a pivoted spring-pressed stepping dog adapted to invariably permit a letter space movement of the carriage upon the depression of a finger key, an arm 45 connected with said stepping dog and adapted to control said holding dog, and a stop carried by said holding dog and normally out of the path of the escapement wheel but adapted to be moved into the path of said 50 escapement wheel to prevent reverse movement thereof when the carriage is retracted.

3. In a typewriting machine, the combination of a carriage, printing keys, an escapement wheel, a vibratory dog carrier, a pivoted 55 spring-pressed holding dog mounted thereon and normally in engagement with the escapement wheel, and a pivoted spring-pressed stepping dog adapted to invariably permit a letter space movement of the carriage 60 upon the depression of a finger key, said stepping dog being provided with an arm adapted to control said holding dog.

4. In a typewriting machine and in a reverse feed escapement, the combination of 65 a carriage, printing keys, an escapement wheel, a vibratory dog carrier, a pivoted spring pressed holding dog mounted thereon and normally in engagement with the escapement wheel, and a pivoted spring-pressed 70 stepping dog adapted to invariably permit a letter space movement of the carriage upon the depression of a finger key, said stepping dog as it moves being also adapted to move 75 said holding dog.

Signed at Syracuse, in the county of Onondaga, and State of New York, this 14th day of August A. D. 1905.

EDWIN E. BARNEY.
